ATTORNEY

UNITED STATES PATENT OFFICE.

WILLIAM W. HAYDEN, OF NEWARK, NEW JERSEY.

DESIGN FOR A MATCH-BOX.

SPECIFICATION forming part of **Design No. 21,638**, dated June 21, 1892.

Application filed May 13, 1892. Serial No. 432,931. Term of patent 3½ years.

To all whom it may concern:

Be it known that I, WILLIAM W. HAYDEN, a citizen of the United States, and a resident of Newark, in the county of Essex and State of New Jersey, have invented and produced 5 a certain new and original Design for Match-Boxes, of which the following is a specification.

Reference is to be had to the accompanying 10 drawing, forming a part of this specification, in which the figure fully illustrates my newly-designed match-box or receptacle for small articles.

A represents the body, and B the top or 15 cover, of the box.

The ornament upon the body of the box consists of the main supporting-bow a, the upper foliage b, and the lower foliage c, sup-

ported by a tendril d at one end of the bow, the upper end terminating in a volute e. The 20 foliage originates at a curved center f, from which also springs the drooping leaf g. The top or cover is also ornamented in relief with the succession of overlapping leaves h, curved over the top, terminating at one end in a divided volute or scroll i and at the other in an elongated stalk j, curved back upon the surface and formed into volutes j j'.

I claim—

The design for a match-box, substantially 30 as shown and described.

WILLIAM W. HAYDEN.
